UNITED STATES PATENT OFFICE

GEORGE R. MORRIS, OF DOLA, WEST VIRGINIA

RAILWAY-SIGNAL HOLDING AND POSITIONING DEVICE

Application filed March 16, 1929. Serial No. 347,609.

This invention relates to railway appliances and has more particular reference to an accessory usable on a railway conveyance, either an engine or car, for carrying and placing in position, audible and visible signalling elements, such as for instance, track torpedoes and fusees.

As is well known, various types and kinds of torpedoes and fusees are used in railway signalling for giving both audible and visible signals, particularly to engineers of oncoming trains, these signal elements being placed on the tracks at danger points, in order to prevent unavoidable collisions and destruction.

Various means and methods have been devised for facilitating the placement of such torpedoes and the like. Under ordinary circumstances in the present practice these devices are placed on the track by hand. On the market now are torpedoes and fusees which are provided with rail clips especially designed to resiliently snap over the head of the rail to aid in holding the signal element in place.

I have evolved and produced a mechanical appliance designed for cooperation with both fusees and torpedoes provided with clips of this type, and the appliance comprises a novel structural arrangement of details which cooperate in an efficient manner for expeditiously placing the elements in position on the track while the train is moving slowly.

The specific details and their especial association will be more readily apparent from the following description and drawings.

In the drawings:

Figure 1 is a side elevation of a fragmentary portion of what may be designated as a portion of an engine showing the device associated with a step equipped platform.

Figure 2 is a rear elevational view of the device removed, with portions shown in section.

Figure 3 is an enlarged vertical sectional view through the supporting and attaching means.

Figure 4 is a horizontal section approximately upon the plane of the line 4-4 of Figure 3.

Figure 5 is a fragmentary view of one of the cam roller equipped signal element clamping devices.

Figure 6 is a fragmentary sectional view showing the manner in which the clamping device is associated with a track rail torpedo.

Figure 7 is a fragmentary rear elevational view of the upper portion of the relatively fixed part of the supporting and attaching means.

Figure 8 is a horizontal section through the clamping jaws showing the canted cam rollers.

Figure 9 is a detail vertical section on the line 9-9 of Figure 5.

Figure 10 is a fragmentary elevational view on an enlarged scale showing the especially designed clamping and retaining means for an ordinary or conventional type of fusee.

Referring now to Figure 1 it will be seen that the reference character 11 designates the movable conveyance which may be an engine, caboose, car, or the like. As before stated the appliance is intended to be attached to any such conveyance and is capable of applying the signal elements while the train is in motion. The appliance is as seen here mounted close to a platform and near the steps in order that the appointed employee may conveniently manipulate it in an expeditious

manner. The reference character 12 designates generally the supporting and attaching means. The supporting and attaching means 12 includes a relatively fixed part 13 which is rigidly fastened to the car 11. The

fixed part 13 is here shown in the form of a vertically disposed flat rectangular body formed at its bottom with a stop lip 14 and formed on its vertical edges with guides 15. This is also formed with a central guide slot

16. Cooperable with this part is a substantially L-shaped hoisting element. This includes a vertical portion 17 having longitudinal flanges 18 slidable in the guides. Also

as seen in Figure 4 this part 17 carries a substantially T-shaped keeper which is cooperable with the slot 16 as clearly shown in Figure 4. The guide, guide flanges, and slots

serve to hold these parts in assembled sliding relation. As seen in Figure 4 the part

17 is provided with a vertical rack 20 with which a pinion 21 on the shaft 22 is engaged. The pinion is in mesh with the rack and the shaft carries a hand crank 23 for convenient manipulation.

5 Referring now to the lower portion of the L-shaped adjusting device it will be seen that this comprises a horizontal or short arm 24. These portions 17 and 24 are of channel shaped cross section seen better in Figure 3. Referring to Figure 3 it will be observed that a bearing block 25 is provided at the upper end of the vertical shaft 26 through which said shaft is journaled. This shaft 26 carries a beveled gear 27 in mesh with the similar bevel gear 28 on the short upper horizontal shaft 29. This shaft 29 is provided with a relatively small hand crank 30 for convenient and individual operation. The lower 10 end of the shaft 26 is journaled in a block 31 and carries a beveled gear 32 in mesh with the complementary gear 33 on a horizontal shaft 34. The shaft 34 is mounted in the lower end portion 24 and it in turn carries a 15 beveled gear 35 meshing with a beveled gear 36 on a rotary carrier shaft 37.

The carrier is generally designated by the reference character 38. As seen in Figure 1 this carrier is provided with three radial 20 arms extending outwardly from the triangular hub 39 which is keyed on the shaft 37 as seen in Figure 2. One pair of the arms is represented by reference characters 40, and the remaining arm by the reference character 41.

Incidentally I might say here that in this triple arm carrier it has been found convenient to construct two of the arms with clamping means for torpedoes and the remaining arm with clamping means for a fusee. 25 The number of clamping means and arms however may be varied according to requirements. Referring for example to Figure 6 it will be seen that the arm 40 has its outer end provided with opposite pairs of ears 42 between which clamping jaws 43 are pivotally mounted as at 44. The lower ends of these jaws are provided with recesses 45 which cooperate with the outturned terminals 46 of a clip 47 designed to engage the head of the 30 track rail 48. This clip carries a conventional torpedo represented at 49. Incidentally the parts 46, 47 and 49 constitute a conventional type of torpedo now marketed, and designed to cooperate with the spring clip. 35 The upper end portions of the jaws are pressed outwardly under the action of coiled springs 50. The reference character 51 designates a plunger which is urged downwardly under the action of the spring 52. This 40 plunger serves to hold the torpedo and its retaining clip between the jaws, while the jaws are in torpedo carrying position. When however, the arms 40 are brought down into vertical alignment with the rail and it is desired to disengage the torpedo, this is done by

novel means for spreading the jaws apart. This means may be of any varied form. For sake of illustration, I have provided, as clearly seen in Figure 5, a pair of tapered outwardly inclined anti-friction rollers 53. 70 These are so related as to slide down against opposite sides of the heads of the rail as represented in Figure 6. In so doing the jaws are spread outwardly to the dotted line position here shown and this disengages the jaws from the retaining clip which carries the torpedoes. Obviously, then, convenient carrying and releasing means is embodied in the rotary carrier. The rotary carrier is operable through the medium of the hand crank, 75 cooperating shaft and beveled gears. 80

The means for holding the fusee in place is substantially the same construction, although there is a slight variation so far as the arm 41 is concerned. Referring to Figure 10 it will be seen that the arm 41 is provided with a socket constructed to accommodate and receive the conventional fusee 53'. This fusee as is usual is provided at its lower end with the head 54 with which the rail engaging clip is connected and is provided at its upper end with the igniting fuse 55 to which the match is attached. The free end of the fuse is exposed so that it may be conveniently lighted. Inasmuch as the features of the clamping means are identical with the features for clamping the torpedo, the same reference characters indicate like parts through the views.

The gist of the invention is in providing an attaching device which may be connected to the movable car, this including a fixed part located at an appropriate element for convenient operation, and vertically adjustable L-shaped parts on which the rotary carrier 100 is mounted and which carries the shafting and operating gears. It is also advantageous to provide a rack and pinion means for raising and lowering the L-shaped device in order that the carrier 38 may be arranged in full 105 line position as seen in Figure 1 or in the elevated dotted line position. When in the dotted line position the carrier is in convenient place for inserting the torpedoes and fusees. When in the full line position the clamping devices may be brought selectively to play by the operating means whereby to release and place the torpedo or fusee in position on the track rail in the manner shown in Figure 6. 110

115 From the foregoing description and drawings it will be seen that I have evolved and produced a novel and simplified railway accessory capable of attachment to an existing railway car in a position over the track rail and so constructed as to permit torpedoes, fusees, and similar signalling elements to be placed in position on the track at any desired point in the course of travel, whereby to avoid certain inconvenience experienced in the pres- 120 125 130

ent method of accomplishing this result. It is thought however that railroad men and other persons skilled in the art to which the invention relates will be able to obtain a clear understanding of the construction and features and advantages after carefully reading the description in conjunction with the drawings. Therefore, a more lengthy description is deemed to be unessential.

10 Although I have shown and described the preferred embodiment of the invention and have emphasized certain details, I wish it to be distinctly understood that minor changes in shape, size, materials and other rearrangements of details such as fall within the scope 15 of the following claims may be resorted to in actual practice if desired.

Having thus described the invention, what I claim as new and desire to secure by Letters Patent is:—

20 1. In a railway signal appliance of the class described, supporting and attaching means comprising a relatively fixed body including guides, a substantially L-shaped hoisting and lowering element having its vertical portion provided with coacting means associated with said guides to hold said element and body together to permit adjustment of the element on the body and a raising and lowering means interposed between the elements and body for actuating the element, and signal carrying and applying means mounted on said hoisting and lowering element.

25 2. A railway signal appliance of the class described, supporting and attaching means comprising a relatively fixed body, a substantially L-shaped hoisting and lowering element, coacting guide means between the element and body, a rack carried by said element, a shaft mounted for rotation on said body and provided with a pinion in mesh with said element whereby to raise and lower said element, a rotary signal carrier and applying device mounted on said element, and operating means carried by said element for actuating said device.

In testimony whereof I affix my signature.
GEORGE R. MORRIS.
